UNITED STATES PATENT OFFICE.

ALLEN P. ASHER, OF SANDPOINT, IDAHO.

FILING-CABINET.

1,384,880.

Specification of Letters Patent. Patented July 19, 1921.

Application filed August 10, 1920. Serial No. 402,611.

To all whom it may concern:

Be it known that I, ALLEN P. ASHER, a citizen of the United States, residing at Sandpoint, in the county of Bonner and 5 State of Idaho, have invented certain new and useful Improvements in Filing-Cabinets, of which the following is a specification.

My present invention relates to improvements in filing cabinets of the extensible and collapsible type, embodying a number of sections, and capable of use as a single unit or section and equally well adapted for enlargement by the utilization of additional 10 sections for increasing the capacity of the cabinet. While I shall hereinafter refer to the cabinet as specially adapted for receiving files of papers or jackets to be stood upon end in the cabinet or units, it will 15 readily be understood that books and other articles may be inclosed within the cabinet in manner similar to book cases &c. With the above mentioned and other objects in view, the invention consists in certain novel 20 combinations of parts and constructions hereinafter described, illustrated in the accompanying drawings, and set forth in the claims appended hereto, it being understood that various changes in the form, proportion, material, and other minor details may 25 be resorted to without departing from the spirit of my invention.

In the accompanying drawings I have 30 illustrated one complete example of a metallic cabinet showing the physical embodiment of my invention according to the best mode I have so far devised for the practical application of the principles of my invention.

40 Figure 1 is a perspective view showing the base, one unit or section and the top members of a cabinet, separated, as embodied in my invention.

Fig. 2 is a transverse sectional view of a 45 cabinet made according to my invention, indicating the manner of superposing the sections or units one upon another, and illustrating also a collapsed unit or section stored in the base for future use.

50 Fig. 3 is a perspective view of a filler utilized in the cabinet to file letter-size papers.

Fig. 4 is a perspective view showing a

rack member or holder adapted for use in the cabinet.

55

Fig. 5 is a perspective view of an enlarged index holder used in the cabinet.

60

In the preferred form of the invention illustrated in the drawings I have utilized a metallic structure in which the base 1, cabinet section 2 and top member 3 are made up of stamped or pressed metal from suitable blanks or shapes, and it will be understood that one or more of the cabinet sections 2 may be used as indicated by the collapsed section 2' inclosed in the base in Fig. 2, and the section 2^a superposed on the section 2, also shown in Fig. 2.

65

The base 1 is in the form of an open, rectangular frame, to form the foundation and support for the superposed cabinet sections or units, and is provided with inwardly extending top flanges 4 to support the section 2, and from which flanges are struck up the vertically disposed tongues 4', two of which 70 are located at each end of the base.

75

Each unit or section as 2, 2' or 2^a is made up of collapsible or foldable members, having a fixed bottom as 5, a hinged back 6, ends 7 and 8 and a front door or plate 9, 80 which is provided with spring hinges 10 to hold it in normally upright position as seen in Fig. 2. The two ends and the back plates of the section are provided with horizontally disposed hinges 11, the hinges of the 85 back plate and the front door being located on a higher plane than the end hinges in order that the latter or end members may be folded in the bottom of the section after which the front and back members 6 and 9 90 are folded over these ends. Thus, when not in use the section may be folded into compact form for shipping, or for storing, as in Fig. 2 wherein the section 2' is stored within the base of the cabinet.

95

Complementary slots 12 are provided in the bottom of each section of the cabinet, to slip over the locking or guiding tongues, as 4' on the base, or over the similar tongues 13, carried in pairs on the ends and back 100 plate respectively of the sections. Thus the lowermost section is rigidly held on the base, and the foldable members of the sections are held in place by the slotted bottom of the section above.

105

The cap or top 3 of the cabinet is pro-

vided, also with slots 14 in its horizontal bottom flange 15 to fit over the tongues on the uppermost section of the cabinet, affording means for rigidly locking the sections together in manner well understood.

In the front of the sections I provide an index holder 16, preferably a metal plate extending longitudinally of the section and fashioned with guide flanges 16' and 16^a 10 to provide a receptacle for the slideable index plates 17, which bear alphabetically arranged letters to be positioned with relation to the files in the cabinet or cabinet section. An added flange 18 of the index holder is 15 projected below the body of the holder and fashioned with open slots 19 to fit over the headed pins 20 projecting inwardly in a horizontal plane from the flange 5^a of the section bottom. The holders are slipped 20 down over the pins and held thereon by friction, thus affording means for supporting the index plates just above the hinge of the front door, where they are visible, and the plates are slideable in the holder to adjust them for use with a large or smaller 25 number of files.

In use the cabinet sections are of a depth and height to receive and retain the longest files, stood upon end or edge, and the sections are also equipped with spacers as 30 21 to adapt them for use with shorter files. Thus the spacers 21, which are made up of angular metal plates of an L shape, are fashioned with integral tongues 21' having up- 35 turned ends, adapted to be passed through and supported in complementary slots 22 properly located in the hinged back plate 6, and the flange 21^a of the spacer, resting on the bottom of the section, affords an abut- 40 ment for the back edge of a comparatively short file jacket 23, as in Fig. 2.

When required, the file holder 24 in Fig. 4 may be used to support the file jackets in the section, and this holder is preferably 45 made of sheet metal, transversely scored in order that it may be bent to angular form as indicated at 25 in dotted lines, and thus ready for use in the cabinet section as desired.

50 When in collapsed or knock-down form, the cabinet is compact and occupies small space, thus rendering it adapted for shipping or storing, and the combination and arrangements of its parts enables the user to 55 erect or dismantle the cabinet with facility

and ease. When assembled, the parts of the sections are held rigidly in place, and the sections, base and top are so locked and held together as to provide a stable support to receive the files, file jackets, books or 60 other articles placed therein.

Having thus fully described my invention, what I claim as new and desire to secure by Letters Patent is—

1. The combination in a filing cabinet, 65 with a base and locking tongues thereon, of a filing section having a fixed, slotted bottom supported on the base, hinged ends and back plate on said section, a superposed member having means for retaining the ends 70 and back plate in rigid normal position, and an openable front door to said section.

2. The combination in a filing cabinet with its base and top member, of a plurality of sections each having foldable ends and 75 rear plate and a front door with spring hinge, and means on the upper section co-acting with means on the lower section for holding said ends and back plate in rigid up-right position, and means for holding the 80 foldable members of the upper section in rigid upright position.

3. The combination with a base having upright tongues, of a file section having a slotted bottom fixed on said tongues, said 85 section having foldable members and tongues on said members, a top section having slots complementary to the tongues on said section, and a normally closed, hinged door in said section. 90

4. The combination in a filing cabinet, of a section as described having slots therein, a detachable L-shaped spacer in said section having tongues to engage said slots, an index holder at the front of the section having a 95 securing flange with slots therein, and pins on said front part of the section to receive said slotted flange.

5. The combination with a base member having a top flange and integral upright 100 tongues, of a file section having a fixed bottom slotted to co-act with said tongues, hinged ends and back plate on said bottom portion each having a pair of tongues at their free edges, a top member having a 105 lower, slotted flange to engage said tongues, and a spring-hinged front door to said section.

In testimony whereof I affix my signature.

ALLEN P. ASHER.
